(57) **CLAIM**

I claim the ornamental design for a golf putter head and hosel assembly, as shown and described.

DESCRIPTION

FIG. 1 is a rear perspective view of the golf putter head and hosel assembly showing my new design in accord with my invention;

FIG. 2 is a front elevational view thereof;

FIG. 3 is a rear elevational view thereof;

FIG. 4 is a top plan view thereof with the hosel pivoted to the left from the right shown in FIG. 1;

FIG. 5 is a bottom plan view of FIG. 4;

FIG. 6 is a left elevational view of FIG. 4;

FIG. 7 is a right elevational view of FIG. 4;

FIG. 8 is a front elevational view of FIG. 4; and,

FIG. 9 is a bottom plan view of another embodiment of the design that is similar to FIG. 5, showing an enlarged and heavier semicircular weight.
